LASTING MACHINE

Eric A. Holmgren, Beverly, Mass., assignor to
 United Shoe Machinery Corporation, Flemington, N. J., a corporation of New Jersey

Application June 4, 1946, Serial No. 674,177

52 Claims. (Cl. 12—14)

1

This invention relates to lasting machines and in most aspects more particularly to machines which last the toe ends of shoes. The invention is herein shown as applied to a power-operated toe-lasting machine which, except as hereinafter noted, may be assumed to be constructed generally as disclosed in United States Letters Patent No. 2,160,846, granted on June 6, 1939, on an application of F. C. Eastman and A. F. Pym, but it is to be understood that it is not limited to an organization of that particular character.

The machine shown in the above-mentioned Letters Patent is provided with wipers supported on a wiper carrier which is moved to advance them bodily lengthwise of a last and relatively to which they are swung or closed inwardly widthwise of the last to embrace an upper closely about the toe end of the last. The wiper carrier is moved heightwise of the last to cause the wipers to perform what is commonly known as an upwiping operation on the toe end of the upper, after which the wipers are further advanced and closed to wipe the lasting margin of the upper inwardly over an insole on the last, the term "lasting margin" referring to that marginal portion of the upper which extends beyond the edge of the insole. In accordance with the disclosure of the above-mentioned Letters Patent the wipers at the limits of their inward wiping movements press a portion of the lasting margin of the upper in upstanding position against a lip on the insole, the machine therein shown being designed especially for the lasting of welt shoes having insoles provided with such lips.

An object of the present invention is to provide a construction suitable for the lasting of shoes of a different type in which the insole has no such lip and in which a portion of the upper wiped inwardly over the insole in generally parallel relation to the bottom of the last is engaged directly by the outsole when the latter is applied to the shoe. In lasting the toes of shoes of that type the upper is wiped farther inwardly over the insole than in welt shoe work, and a portion of its lasting margin located at a substantial distance from the edge of the insole usually needs to be trimmed off before the outsole is applied. To facilitate such trimming of the upper after the lasting operation it has been proposed heretofore to provide in a lasting machine means serving as an abutment against which the portion of the lasting margin of the upper which it is desirable thus to remove is pressed by the wipers in upstanding relation to the shoe bottom at the end of the inward-wiping move-

2

ments of the wipers. The machine herein shown includes a device which serves that purpose, this abutment device having an upper-engaging face curved to extend in substantially parallel relation to the edge of the insole about the end and along the sides of the toe when positioned at a substantial distance inwardly from the edge of the insole. To render the wipers most effective in pressing the upper against this device, so that the portion of the upper which is to be trimmed off will be sharply defined, it is desirable that the edges of the wipers conform substantially to the contour of the portion of the upper pressed against the device, i. e., to the contour of the upper-engaging face of the device with suitable allowance for the thickness of the upper materials. In that case, however, the edges of the wipers will not conform very closely to the curvature of the upper opposite the edge face of the insole and accordingly the wipers will not be adapted to act in the most effective manner to wipe the upper heightwise of the last at and near the edge of the insole. In view of these and other considerations, the present invention, in one aspect, provides a construction whereby the wiping of the upper heightwise of the last is performed by means other than the wipers which wipe it inwardly over the insole and press it against the above-mentioned abutment device, so that the edges of the wipers may be curved to conform substantially to the contour of the upper pressed against that device without detracting from the effectiveness of the upwiping operation on the upper. As herein illustrated, this other wiping means comprises a wiping plate recessed to embrace the toe end of the shoe and last and having a wiping edge curved to conform substantially to the contour of the upper opposite the edge face of the insole, the plate being supported by the wiper carrier to be moved thereby heightwise of the last. In order that the plate will not be carried too far toward the shoe by the movement of the wiper carrier lengthwise of the shoe prior to the beginning of the upwiping operation, which might result thereafter in too much pressure of the plate on the upper at the end of the toe in view of the character of the heightwise curvature of the end of the toe in shoes of some styles, provision is afforded for relative movement of the plate and the wiper carrier lengthwise of the shoe and for adjustably limiting the movement of the plate toward the shoe in the course of the movement of the wiper carrier in that direction. The plate is further controlled by a spring against the resistance

of which it may move lengthwise of the shoe relatively to the wiper carrier in response to pressure of the upper thereon in the upwiping operation. It will be evident that in some aspects involving the use of different means for performing the upwiping operation and the wiping of the upper inwardly over the insole respectively the invention is not limited in utility to the lasting of shoes of the type herein shown, but is applicable, for example, to the lasting of welt shoes where a portion of the upper is pressed by the wipers against a lip on the insole.

For purposes of this invention also the above-mentioned abutment device against which a portion of the lasting margin of the upper is pressed by the wipers is associated with means for positioning the shoe heightwise independently thereof by engagement with the insole and is movable relatively to this positioning means in directions heightwise of the shoe to permit it to adjust itself to the shoe, additional means being provided for positioning the shoe lengthwise and laterally. In the construction shown the device is so positioned and controlled as to serve additionally as a holdown for the margin of the insole at the end of the toe to prevent displacement of that portion of the insole in the lasting operation. From its initial position where it serves that purpose it is pushed inwardly lengthwise of the shoe by the wipers against the resistance of a spring until it is positively stopped at the proper distance from the end of the toe to serve as an abutment in the manner above described. In its inward movement over the insole the device has the additional function of a retarder, insuring that the upper about the end of the toe will be wiped tightly and smoothly over the insole by the wipers. In this aspect, in the construction herein shown, the device supplements the action of another retarder which is substituted for the grippers disclosed in the previously mentioned Letters Patent and clamps the marginal portion of the upper outspread on the upwiping plate to apply a pull to the upper and to control it in the upwiping operation.

Since the insole of a shoe of the type above referred to has no lip by engagement with which the shoe may be positioned lengthwise and laterally in the manner disclosed in the previously mentioned Letters Patent, the invention further provides novel means for positioning the shoe in these respects. The construction herein shown includes for this purpose an end gage and side gages arranged to serve as shoe-positioning abutments opposite the end and side faces of the toe-end portion of the last respectively, and also other gages arranged to engage the opposite sides of the forepart of the shoe in locations farther heelward than its toe-end portion. These other gages, as also the toe side gages, are connected together for equal movements toward or from each other and are arranged to be forced apart by wedging action of the shoe thereon when the shoe is presented to the machine, the position of the shoe lengthwise being determined by contact of the end gage with the toe-end face of the last. In the course of the operation of the machine the there toe gages are withdrawn from their operative positions by novel means operated by the movement of the wiper carrier heightwise of the last while the other gages remain in their shoe-engaging positions.

The novel features of the invention, including various novel details of construction and

combinations of parts, will now be more particularly described with reference to the accompanying drawings and thereafter pointed out in the claims.

5 In the drawings,

Fig. 1 is a view in right-hand side elevation of a portion of the machine shown in the previously mentioned Letters Patent as modified for purposes of the present invention;

10 Fig. 2 is an enlarged view, partly in right-hand side elevation and partly in section, of the upper portion of the structure shown in Fig. 1;

Fig. 3 is a plan view of the means for wiping the toe end of the upper into lasted position;

15 Fig. 4 is a perspective view of the upwiping plate and of parts associated therewith;

Fig. 5 is a view partly in plan and partly in section on the line V—V of Fig. 2, showing the means for positioning the shoe lengthwise and laterally;

20 Fig. 6 is a view in rear elevation of the shoe-positioning means shown in Fig. 5;

Fig. 7 is a section on the line VII—VII of Fig. 6;

25 Fig. 8 is a view in front elevation of a portion of the shoe-positioning means;

Fig. 9 is a view in right-hand side elevation of the retarder which clamps the upper on the upwiping plate and of parts associated therewith;

30 Fig. 10 is a view partly in front elevation and partly in section of the structure shown in Fig. 9;

Fig. 11 is a view in rear elevation of the device against which a portion of the lasting margin of the upper is pressed by the wipers, and of parts associated therewith;

35 Fig. 12 is a section on the line XIII—XII of Fig. 11;

Fig. 13 is a section on the line XIII—XIII of Fig. 12;

40 Fig. 14 is a view partly in right-hand side elevation and partly in section, showing the parts in the vicinity of the shoe as they appear in relation to the shoe after the clamping of the shoe but prior to the beginning of the movement of the wiper carrier.

Fig. 15 is a view similar to Fig. 14, showing the parts as they appear substantially at the beginning of the unwiping operation;

45 Fig. 16 is mainly a plan view with the parts in the same positions as in Fig. 15;

Fig. 17 is a view similar to Fig. 15 showing the parts as they appear just after the beginning of the movements of the wipers for wiping the upper inwardly over the insole;

50 Fig. 18 is a view similar to Fig. 17 with the parts as they appear when the wipers are at the limits of their inward wiping movements; and

Fig. 19 is mainly a plan view with the parts in the same positions as in Fig. 18.

60 For positioning a shoe heightwise relatively to the toe-lasting means the machine herein shown is provided with means corresponding generally to the disclosure of Letters Patent No. 2,385,414, granted on September 25, 1945, on an application of mine. That is, there is mounted in a top frame casting 2 a vertical rod 4 which is adjustably movable upwardly or downwardly by a member 6 confined for turning movement on a diametrically reduced upper end portion of the rod and threaded

65 in the frame casting. Formed on the lower end of the rod is a head 8 (Fig. 12) on which is supported a block 10 having fast thereon three downwardly extending pins 12 (Fig. 13) the lower end faces of which are arranged to engage the bottom face of the forepart of the insole, one of

the pins engaging it comparatively near the end of the toe and the others farther from the end of the toe in locations spaced apart widthwise of the shoe. The pins thus have virtually a three-point bearing on the insole and thereby position the shoe bodily heightwise and also with respect to tipping movements. As shown, the lower end faces of the pins are somewhat inclined to correspond approximately to the usual convex curvature of the bottom of the forepart of the last. The block 10 has on its opposite sides curved flanges 14 (Fig. 11) supported on similarly curved inwardly extending flanges 16 formed on plates 18 secured to the opposite sides of the head 8. The block with its pins 12 is thus guided for adjustment about an axis extending widthwise of the shoe to position the pins properly in accordance with variations in the lengthwise curvatures of the bottoms of the foreparts of shoes of different styles. To effect this adjustment there is slidingly mounted in the head 8 a rack bar 20 in engagement with teeth formed on the block 10. Threaded in this rack bar is a rod 22 having on its front end a knob 24 for turning it. The rod is held against lengthwise movement by a flange 26 on the head 8 in engagement with a flange 28 on the rod and with the knob 24. The toe end of the shoe is clamped against the lower ends of the pins 12 by a toe rest 30 which is moved upwardly into clamping position substantially at the beginning of the cycle of power operations of the machine.

To position the shoe lengthwise and laterally when it is presented to the machine there are provided a plurality of gages, including an end gage 32 (Figs. 2 and 6) arranged to serve as an abutment in engagement with the toe-end face of the last to determine the position of the shoe lengthwise and a pair of opposite side gages 34 arranged to serve as abutments opposite the side faces of the toe-end portion of the last in engagement with the upper on those faces. The end gage 32 consists of a bar 36 mounted for sliding movements in directions heightwise of the shoe along a guideway 38 formed in a block 40 which is secured by two screws 42 to the frame casting 2 and provides part of a lower bearing for the vertically adjustable rod 4. When a shoe is in position in the machine the guideway 38 is over the extreme toe end of the shoe bottom. The bar 36 is secured to a downwardly extending portion of a controlling member 44 through which the gage 32 is moved into and out of operative position by means hereinafter described, the downwardly extending portion of the controlling member being movable along a guideway 46 (Fig. 2) in the block 40. The opposite side gages 34 comprise shoe-engaging knobs 48 fast on the lower ends of rods 50 which are guided for vertical movements into and out of operative positions in bearings formed in adjusting members 52 mounted to swing about vertical rods 54 extending through upper and lower pairs of outwardly extending arms 56 and 58 formed on the block 40. The arms 56 underlie inwardly extending arms 60 formed on the adjusting members 52 and accordingly support these members, and the arms 58 overlie inwardly extending arms 62 on the lower ends of the adjusting members. The rods 54 are supported by screws 64 threaded in the lower end portions of the adjusting members 52 and extending into annular recesses 66 in the rods. It will thus be seen that the side gages 34 are movable toward or from each other in directions widthwise of the shoe by swinging movements of

the adjusting members 52 about the axes of the rods 54.

Mounted for turning movements on the top of the block 40 about studs extending upwardly from the block are two pinions 68 which are in mesh with each other and which engage respectively gear teeth 70 formed on the inwardly extending arms 60 of the adjusting members 52. Accordingly the side gages 34 are connected together for equal swinging movements toward or from each other. Connected to a lug 72 on one of the members 52 and to a pin 74 in the other member is a spring 76 which tends to swing the members in the directions to carry the side gages 34 toward each other, the pin 74 being movably mounted and having threaded thereon a thumb nut 78 whereby the tension of the spring may be varied. Such movements of the side gages toward each other are limited by a stop screw 80 which is threaded in a block 82 fast on a web 84 formed on the frame casting 2 and engages an arm 86 formed on one of the members 52. It will thus be seen that the normal distance between the side gages 34 may be varied by turning the screw 80. The adjustment is preferably such that when the operator in presenting a shoe to the machine moves it lengthwise toward the end gage 32 the side gages 34 are forced somewhat apart by wedging action of the shoe thereon to insure that these gages will properly perform their centralizing function on the toe-end portion of the shoe. The side gages are movable in directions heightwise of the shoe into and out of their operative positions by sliding movements of the rods 50 in their bearings in the members 52, the means whereby such movements are effected, together with corresponding movements of the end gage 32, being hereinafter described.

For greater precision in the positioning of the shoe before it is clamped by the toe rest against the pins 12 the machine is further provided with another pair of side gages 88 arranged to engage the opposite sides of the forepart of the shoe in locations farther heelward than its toe-end portion. These gages comprise three-armed levers 90 (Fig. 8) provided with downwardly extending arms 92 which engage the shoe and mounted for swinging movements about axes extending lengthwise of the shoe on studs 94 fast in a plate 96 which is secured on the front of the frame casting 2. Other arms 98 of these levers extend inwardly toward each other and are provided with intermeshing gear teeth 100. Accordingly the side gages 88 are connected together for equal movements toward or from each other widthwise of the shoe. The third arms 102 of the three-armed levers extend upwardly and are forked to provide supports for trunnion blocks 104 between which is a spring 106 which tends to move the side gages 88 toward each other. Extending through this spring is a rod 108 which is mounted to turn in one of the trunnion blocks 104 and is threaded in the other trunnion block, the rod having fast on one end a knob 110 engaging the adjacent trunnion block to limit movements of the side gages toward each other by the spring 106. It will be understood that by turning the rod 108 the side gages are adjusted equal distances toward or from each other, the adjustment being preferably such that the gages are initially somewhat nearer together than the width of the portion of the shoe which they engage to insure that they will be properly effective on the shoe. Inclined faces 112 on the gages 88 are arranged to be engaged

by the shoe to force the gages apart by wedging action of the shoe thereon as the shoe is presented to the machine, such action of the shoe on the gages resulting from heightwise movement of the portion of the shoe which they engage. That is, in presenting the shoe to the machine and moving it lengthwise toward the end gage 32 and between the toe side gages 34 the operator tips its heel end upwardly to cause the portion of its forepart which is located farther heelward than its toe-end portion to enter the space between the side gages 38 and to spread these gages.

After the shoe has been clamped against the pins 12 by the toe rest 30 in the position determined by the pins and by the several gages, and after a heel rest (not shown) has been moved into engagement with the heel-end face of the shoe as disclosed in Letters Patent No. 2,160,846 to assist in holding the shoe against lengthwise displacement, the toe end of the shoe is lasted by means which will now be described. For wiping the lasting margin of the upper inwardly over the insole the machine is provided with a pair of wipers 114 (Figs. 2 and 3) supported on wiper holders 116 which are guided for movements in curved paths on a wiper carrier 118 to close the wipers inwardly widthwise of the shoe as disclosed in the last-mentioned Letters Patent. As also therein disclosed, the wiper carrier is supported for movements to advance and retract the wipers lengthwise of the shoe on a pair of swinging links 120, these links being spaced apart widthwise of the shoe and being pivotally connected at their upper ends to the front end portion of the carrier, and on the upper end of a lever 122 pivotally connected by a pin 124 to the rear end portion of the carrier and mounted between its upper and lower ends on a fulcrum pin 126. The upper arm of the lever 122 thus serves, in effect, as a link substantially parallel to the links 120. The two links 120 are pivotally connected at their lower ends to arms 128 fast on a rockshaft 130, and also fast on this rockshaft is an arm 132 provided with a roll 134 which lies in a cam track 136 formed in a cam member 138 fast on a cam shaft 140. Through this mechanism the wiper carrier 118 is swung upwardly about the pin 124 for wiping the toe end of the upper heightwise of the last, this upwiping operation in the machine herein shown being performed by means other than the wipers 114, as more particularly hereinafter described. To advance and retract the wiper carrier lengthwise of the shoe the lever 122 is swung about the pin 126 by a cam track 142 formed in one side of a gear wheel 144 through which the cam shaft 140 is operated, the lever carrying a roll 146 which lies in this cam track.

For operating the wiper holders 116 to close the wipers widthwise of the shoe the holders are connected by links 148 to a slide 150 guided for movements lengthwise of the shoe on the wiper carrier 118, and as more fully disclosed in Letters Patent No. 2,160,846 this slide is operated through means including yieldable spring mechanism 152 (Fig. 3) by a bell-crank lever 154 (Fig. 1) pivotally mounted at 156 on the wiper carrier. The bell-crank lever 154 is connected by a link 158 to an arm 160 fast on a rockshaft 162, and also fast on this rockshaft is an arm 164 provided with a roll 166 lying in a cam track 168 formed in one side of the previously mentioned gear wheel 144. It will be understood that the spring mechanism 152 is yieldable in response to

resistance encountered by the wipers, as herein-after more fully explained, at the end of their inward wipe on the upper.

The cam tracks 142 and 168 by which respectively the wipers are advanced lengthwise of the shoe and are closed widthwise of the shoe are shaped differently from the corresponding cam tracks shown in the last-mentioned Letters Patent, mainly for the purpose of eliminating the partial retractive movements and the second advancing and closing movements of the wipers provided for by the earlier construction in the wiping of the upper over the insole. For reasons which will hereinafter appear the cam track 142 is so shaped as to impart in the same manner as heretofore a preliminary advancing movement to the wiper carrier toward the shoe prior to the upwiping operation, the wipers, however, being maintained in their fully open positions by the cam track 168 until after the upwiping operation.

To perform the upwiping operation there is provided a wiping plate 170 (Figs. 2, 3 and 4) formed to embrace the upper about the toe end of the last and having a wiping edge 172 curved to conform substantially to the curvature of the upper opposite the edge face of the toe end of the insole. The plate 170 is supported partly by the top faces of the wipers 114 and partly by a controlling member 174 having a rearwardly extending arm 176 on which a rearwardly extending portion of the plate rests, the wipers and their holders 116 having suitable slots therein to provide room for this member. The position of the plate relatively to the controlling member is determined by a pin 178 extending upwardly from the controlling member into a hole in the plate and by another pin 180 extending upwardly from the rear end of the arm 176 into an open slot 182 in the rear end of the plate. A diametrically enlarged portion 184 of the pin 178 is mounted in a guideway in the member 174 and by means of a pin 186 extending forwardly therefrom may be moved downwardly against the resistance of a spring 188 to release the plate 170 when it is desired to substitute a plate of different contour. The controlling member 174 is mounted for movements in directions lengthwise of the shoe relatively to the wiper carrier 118 along guideways provided by members 190 secured to the lower face of the wiper carrier. A spring 192 extending into a socket in the member 174 and abutting at its rear end against a block 194 secured to the wiper carrier holds the member normally in a position determined by the engagement of shoulders thereon with stops 196 fast on the front ends of the members 190. Further to assist in controlling the plate 170 there is secured to the lower face of a cover plate 198 on the wiper carrier a member 200 provided with a slot 202 into which the upper end of the pin 180 extends. By engaging the rear end portion of the plate 170 the member 200 prevents the plate from tipping in the upwiping operation. It will thus be seen that when the wiper carrier is moved preliminarily lengthwise of the shoe toward the toe prior to the upwiping operation the upwiping plate 170 is carried thereby into position to render it effective on the toe end of the upper in the upward swinging movement of the carrier. In order to prevent the plate from being carried too far under the end of the toe in the operation of the machine on shoes of some styles, with the result that the plate would thereafter apply too much pressure to portions of the upper in the upwiping operation, mechanism is provided for

adjustably limiting the movement of the plate toward the shoe. This mechanism comprises a stop lever 204 pivotally mounted at 206 on a bracket 208 which is fast on a portion 210 of the frame of the machine, the lever having on its upper end a roll 212 arranged to be engaged by an arm 214 extending downwardly from the controlling member 174. The position of the lever 204 is determined adjustably by a screw 216 which is threaded therein and engages the bracket 208. A spring 218 connected to the lever and to the bracket holds the screw normally against the bracket. It will be understood that when the wiper carrier is moved toward the shoe prior to the upwiping operation the arm 214 is carried into engagement with the roll 212 which limits the movement of the member 174 and the plate 170 toward the shoe while permitting further movement of the wiper carrier against the resistance of the spring 192. In the course of the upwiping operation the spring 192 may yield to permit the plate 170 and the member 174 to move relatively to the wiper carrier in response to pressure of the upper at the end of the toe on the plate if the contour of the toe is such as to produce this result.

Instead of the grippers shown in Letters Patent No. 2,160,846 for pulling the upper and for controlling it during a portion of the lasting operation, the machine herein shown is provided with a retarder identified generally by the reference character 220 (Figs. 9 and 10) for yieldingly clamping the marginal portion of the upper outspread on the upwiping plate 170 to cooperate with the plate in applying a pull to the upper in the upwiping operation. This retarder is in many respects similar in construction to a retarder shown in Letters Patent No. 2,349,815, granted on May 30, 1944, on an application of F. C. Eastman's, but differs therefrom in some respects, partly to avoid interference with the end gage 32. It includes a pair of upper-clamping members 222 each arranged to engage the upper along one side and part way around the end of the toe. Upwardly extending portions 224 of these members, in the construction shown, are mounted on pins 226 projecting in directions widthwise of the shoe from the lower ends of a pair of links 228 the upper ends of which are rotatably mounted on a rod 230 secured midway between its opposite ends in an upwardly and downwardly extending bar 232 controlled as hereinafter described. The members 222 are thus supported for adjusting movements toward and from each other along the pins 226. The retarder further includes a central upper-clamping member 234 arranged to bridge any space between the two members 222 at the end of the toe and provided with ears 236 mounted on cylindrical projections 238 on the links 228. The member 234 overlaps flat faces on the members 222 in such manner that all three members maintain a fixed relation to one another with respect to movement about the axes of the pins 226. The links 228 engage opposite side faces of the bar 232 and are held against these faces by plates 240 secured to the bar by screws 242. Extending through holes in the plates are sleeves 244 formed on the links 228, and mounted to turn on these sleeves are the hubs 246 of latches 248 which extend into grooves formed in the upwardly extending portions 224 of the retarder members 222. Threaded on the rod 230 are thumb nuts 252 provided with flanges 254 which lie in grooves formed in the hubs 246, so that by the turning of these nuts the retarder

members 222 are adjusted toward or from each other through the latches 248. Springs 254 connected to the hubs of the latches tend to swing the latches in clockwise directions with reference to Fig. 9 and thereby hold them normally connected to the members 222. By means of arms 256 projecting from the hubs 246 the latches may be disconnected from the members 222 to permit the latter to be removed from the pins 226 when it is desired to substitute members of different shapes.

The central member 234 of the retarder is further connected to the lower end of the bar 232 by a link 258. Accordingly the retarder is supported by the pair of links 228 and the link 258 for tipping movements to permit it to adjust itself to the inclination of the upwiping plate 170 when it first clamps the upper thereon (Fig. 15) and to maintain its parallel relation to the plate as the latter is swung upwardly to a substantially horizontal plane in the upwiping operation. The relation of the links to one another is such that the retarder is controlled substantially in the same manner as disclosed in Letters Patent No. 2,349,815, its tipping movements being about an axis determined by the links and located substantially on its upper-engaging face at substantial distances from its opposite ends measured lengthwise of the shoe.

30 The bar 232 is pivotally supported between its upper and lower ends on a pin 260 (Fig. 2) carried by an arm 262 which is mounted on a rockshaft 264 supported in bearings on the top frame casting 2. The bar is further controlled by an arm 266 pivotally connected at 268 to its upper end and mounted to swing about the axis of a pin 270 on the casting 2. Integral with the arm 262 is an arm 272 which carries a trunnion block 274, and rotatable in this trunnion block is a spindle 276 which is threaded in another trunnion block 278 carried by an arm 280 fast on the rockshaft 264. The spindle 276 is prevented from moving lengthwise relatively to the trunnion block 274 by a flange 282 on the spindle engaging one side of the trunnion block and by a knob 284 fast on the spindle and engaging the other side of the trunnion block. The two arms 262 and 272 are rotatably mounted on the rockshaft 264, and accordingly by the turning 45 of the spindle 276 they may be moved about the rockshaft to adjust the retarder 220 in directions heightwise of the shoe. Also fast on the rockshaft 264 is an arm 286 (Fig. 1) connected by a link 288 to one arm of a bell-crank lever 290 mounted to turn on the previously mentioned shaft 162, and the other arm of this bell-crank lever carries a roll 292 engaged by the periphery of a cam 294 on the cam shaft 140. A spring 295 connected to the bell-crank lever holds the roll 60 normally against the cam, and at a time in the operation of the machine when a drop *a* on the cam arrives in a position opposite the roll the spring acts through the mechanism described to move the retarder downwardly into position for 55 clamping the upper on the plate 170 when the plate in its upward movement arrives in position to cause such clamping action to take place. As the plate is thereafter moved farther upwardly to perform the upwiping operation on the upper the retarder is lifted by the plate against the resistance of the spring 295, the roll 292 being carried somewhat away from the cam 294. In this operation the retarder is pressed on the upper not only by the spring 295 but also by a 65 70 75 spring 296 one end of which is connected to an

arm 300 fast on the rockshaft 264 and the other end of which is connected to a lever 302 by which the tension of the spring 298 may be varied to vary the amount of clamping pressure applied to the upper. After the upwiping operation, at a time when a rise b on the cam 294 arrives in position to engage the roll 292, the retarder is moved upwardly to its initial position away from the plate 170.

In order that the upwiping plate 170 and the wipers 114 may perform the required operations on the upper it is necessary that the end gage 32 and the two side gages 34 be withdrawn from their operative positions. The previously mentioned gage-controlling member 44 which is secured to the vertically movable bar 36 of the end gage has fast thereon a plate 304 (Figs. 2, 5 and 6) which extends into grooves formed in spools 306 secured on reduced upper ends of the rods 50 of the side gages 34. By this plate, therefore, connection is maintained between the end gage and the side gages in all positions of adjustment of the side gages. The member 44 is connected by a link 308 to an arm 310 fast on a rockshaft 312 which is mounted in bearing members 314 secured to the frame casting 2. Also fast on the rockshaft is another arm 316 provided with a pin 318 which extends through a slot 320 (Fig. 2) formed in a link 322, this link being pivotally connected at its lower end to a block 324 fast on the cover plate 198 of the wiper carrier 118. A spring 326 connected to the pin 318 and to the link 322 holds the pin normally at the lower end of the slot 320, so that the normal positions of the gages 32 and 34 are determined by the wiper carrier. When the wiper carrier is swung upwardly after the shoe has been clamped against the pins 12 by the toe rest 30 it acts through the link 322 and the arm 316 to turn the rockshaft 312 and thereby to impart upward movement to the arm 310 to withdraw the gages from their operative positions. The slot 320 is provided in the link 322 to avoid any danger of damage through possible contact of the gages with the shoe in the return of the parts to starting positions.

To facilitate the trimming of the toe end of the upper to remove the surplus marginal portion of the upper materials after the shoe leaves the machine, there is provided a plate 328 (Figs. 11, 12 and 13) having a downwardly extending rim 330 arranged to engage the bottom face of the toe end of the insole and an abutment face 332 curved to extend in substantially parallel relation to the edge of the insole and against which a portion of the lasting margin of the upper is pressed in upstanding relation to the shoe bottom by the wipers 114 when the wipers are at the limits of their inward wiping movements over the insole, the wipers being so shaped that their wiping edges conform substantially to the curvature of the portion of the upper pressed against the abutment face 332. The plate 328 is provided with a slot 334 through which the shoe-positioning pin 12 nearest the end of the toe extends and also has a tail portion 336 arranged to extend lengthwise of the shoe between and in engagement with flat faces (Fig. 16) on the other two pins 12. The plate is supported by a latch 338 which extends downwardly through a slot 340 therein and under a shoulder 342 on the plate, the latch being formed on a bar 344 which is movable in directions lengthwise of the shoe along guideways on the block 10. Extending into a slot 346 in this bar is a flange 348 formed on a knob 350 which is fast on

the front end of a pin 352 movably mounted in the block 10 and held normally in the position shown in Fig. 12 by a spring 354. By means of the knob 350 the operator may move the pin 352 against the resistance of the spring 354 to cause the latch 338 to release the plate 328 when it is desired to substitute a plate of different contour. The plate is engaged on its top face near the end of the toe by a presser member 356 vertically movable in guideways in the block 10 and pressed downwardly by a spring 358 which abuts at its upper end against a pin 360 in the block, the pin extending through a slot 362 in the presser member. Also engaging the top face of the plate 328 in locations farther from the end of the toe are two pins 364 spaced apart widthwise of the shoe and pressed downwardly by springs 366. The plate is therefore movable upwardly against the resistance of the springs 358 and 366 by pressure of the shoe thereon when the shoe is forced upwardly by the toe rest 30 into engagement with the shoe-positioning pins 12, and since it is thus movable relatively to these pins and may also tip longitudinally of the shoe it is permitted to adjust itself to the bottom of the shoe. The plate is so positioned initially lengthwise of the shoe under control of the spring 354 that it serves as a holdown to prevent displacement of the margin of the insole at the end of the toe in the upwiping operation. As the wipers 114 wipe the upper inwardly over the insole they act through the upper to force the plate inwardly lengthwise of the shoe against the resistance of the spring 354 until the inward movement of the plate is stopped by the end pin 12 which extends through the slot 334 in the plate, the plate being guided in its inward movement by the three pins 12 and the latch 338 moving with the plate. After its inward movement the plate is controlled positively by the end pin 12 and serves as an abutment against which a portion of the lasting margin of the upper is pressed by the wipers at the end of the toe and also along the sides of the toe.

The manner of operation of the machine, in so far as it is of interest with reference to the present invention, will now be briefly summarized. In presenting a shoe to the machine the operator moves it lengthwise toward the end gage 32 to bring the toe-end face of the last into contact with that gage while forcing the two side gages 34 apart by wedging action of the toe-end portion of the shoe thereon, the bottom of the toe end of the insole engaging the plate 328 which at that time extends downwardly beyond the lower ends of the pins 12. At the same time the operator swings the heel end of the shoe upwardly to cause its ball portion to enter the space between the two other side gages 34 and to force these gages apart by contact with their inclined faces 112. It will be understood that before the shoe is thus presented suitable cement will have been applied to the margin of the toe end of the insole and between the different layers of the upper materials. For convenience the drawings show only two such layers, but it will be understood that the toe end of the upper materials will usually include three or more layers.

After having thus presented the shoe the operator starts the power operation of the machine, whereupon the toe rest 30 is moved upwardly to clamp the shoe against the lower ends of the pins 12, the plate 328 being lifted by 75 the shoe against the resistance of the springs

358 and 366 (Fig. 12) until the shoe engages the pins. The positions of the parts at the time when the shoe is thus clamped between the pins 12 and the toe rest are as illustrated in Fig. 14. As hereinbefore explained, also, a heel rest (not shown) is moved into engagement with the heel-end face of the shoe. After the clamping of the shoe the wiper carrier 118 is moved lengthwise of the shoe toward its toe end and is swung upwardly to bring the unwiping plate 170 into position for effectively wiping the upper heightwise of the last in response to further upward movement of the carrier, the wipers 114 also being carried toward the toe end of the shoe but being held retracted lengthwise of the shoe from the edge of the plate 170 and being also maintained in their open positions. By the movement of the wiper carrier lengthwise of the shoe the arm 214 of the plate-controlling member 174 is carried into engagement with the roll 212 on the stop lever 204 to limit the movement of the plate 170 toward the shoe as determined by the adjustment of the stop lever, the spring 192 then yielding in response to such further movement as the wiper carrier thereafter receives. In the course of the above-described movements of the wiper carrier the retarder 220 is moved downwardly into position for clamping the marginal portion of the upper outspread on the plate 170 as soon as the plate arrives in position to cause such clamping action to take place. The positions of the parts at the time when the marginal portion of the upper is first clamped on the plate 170 are substantially as illustrated in Figs. 15 and 16, the gages 32 and 34 having at this time been moved upwardly a short distance through the mechanism provided for that purpose in response to the upward movement of the wiper carrier.

As the wiper carrier continues its upward swinging movement the toe end of the upper is wiped heightwise of the last by the plate 170 and the retarder is lifted by the plate against the resistance of its controlling springs 296 and 293 through which it is pressed on the upper, an upward pull being thus applied to the upper while its marginal portion slips more or less inwardly toward the last between the plate and the retarder. In this operation the roll 292 is carried a short distance away from the periphery of the cam 294. In the course of the upwiping operation, moreover, the gages 32 and 34 are moved farther upwardly to their inoperative positions, the gages 88, however, remaining in contact with the shoe since they are not in positions to interfere with the toe-lasting operation. After the upwiping operation the wipers 114 are advanced and closed to wipe the marginal portion of the upper inwardly over the insole, the positions of the parts when these wipers are just beginning to act on the upper being substantially as shown in Fig. 17. Immediately thereafter the rise b on the cam 294 (Fig. 1) acts on the roll 292 to move the retarder upwardly away from the plate 170, thus releasing the margin of the upper. As the wipers 114 are moved farther inwardly they act through the upper on the end of the plate 328, which serves as a holdown for the margin of the insole at the end of the toe during the upwiping operation, to force this plate inwardly lengthwise of the shoe, together with the latch 336, against the resistance of the spring 354 (Fig. 12) until the movement of the plate is stopped by the end pin 42 in the slot 334 when the wipers are substantially at the limits of their inward wiping movements. In this operation the plate has the function of a

supplemental retarder for controlling the margin of the upper at the end of the toe. As illustrated in Figs. 18 and 19, the wipers at the limits of their inward movements press a portion of the lasting margin of the upper in upstanding position against the plate 328 about the end and along the sides of the toe to facilitate the removal of this upstanding surplus portion of the upper materials after the toe-lasting operation. In this action the wipers are yieldingly controlled with respect to their closing movements by the spring mechanism 152 (Fig. 3) and with respect to their movements lengthwise of the shoe by other spring mechanism not herein shown but disclosed in Letters Patent No. 2,160,846. When the parts are in the positions shown in Figs. 18 and 19 the machine preferably comes to a stop, at the same time in the cycle as the second stop provided in accordance with the disclosure of Letters Patent No. 2,160,846, to permit the toe end of the upper to remain under the pressure of the wipers for a few seconds while the cement is setting. Thereafter the operator again starts the machine, whereupon the parts are returned to their starting positions. It will be understood that the spring 354 which controls the plate 328 is not of sufficient strength to disturb the lasted marginal portion of the upper at the end of the toe when the wipers 114 are retracted and the toe rest 30 is moved downwardly, even though the plate 30 may still be against that portion of the upper for a brief interval before the shoe is removed from the machine by the operator.

Having described my invention, what I claim as new and desire to secure by Letters Patent of the United States is:

1. In a lasting machine, wipers movable to wipe the marginal portion of an upper about the toe end of a last inwardly over an insole on the last, a device arranged to engage the insole and to serve as an abutment against which a portion of the lasting margin of the upper around the toe is pressed by the wipers in upstanding relation to the shoe bottom at a distance inwardly from the edge of the insole at the end of the wiping operation, the wipers being shaped to conform substantially to the contour of the portion of the upper pressed against said device, and other wiping means shaped to conform substantially to the contour of the upper opposite the edge face of the insole for wiping the upper about the toe end of the last heightwise of the last before said wipers wipe it inwardly over the insole and against said abutment device.
2. In a lasting machine, wipers movable to wipe the marginal portion of an upper about the toe end of a last inwardly over an insole on the last, a device arranged to engage the insole and to serve as an abutment against which a portion of the lasting margin of the upper around the toe is pressed by the wipers in upstanding relation to the shoe bottom at a distance inwardly from the edge of the insole at the end of the wiping operation, the wipers being shaped to conform substantially to the contour of the portion of the upper pressed against said device, and a plate having a wiping edge curved to extend about the toe from one side thereof to the other side and to conform substantially to the contour of the upper opposite the edge face of the insole for wiping the toe end of the upper heightwise of the last before the wipers wipe it inwardly over the insole and against said abutment device.
3. In a lasting machine, wipers movable to wipe the marginal portion of an upper about the

15

toe end of a last inwardly over an insole on the last, a device arranged to engage the insole and to serve as an abutment against which a portion of the lasting margin of the upper around the toe is pressed by the wipers in upstanding relation to the shoe bottom at a distance inwardly from the edge of the insole at the end of the wiping operation, the wipers being shaped to conform substantially to the contour of the portion of the upper pressed against said device, a wiper carrier supporting said wipers and movable to carry them heightwise of the last before they wipe the upper inwardly over the insole, and other wiping means supported by said wiper carrier at the opposite sides of said wipers from the sides thereof which face the insole when they are over the insole, said other wiping means being arranged to wipe the upper about the toe heightwise of the last in response to the movement of the wiper carrier and being shaped to conform substantially to the contour of the upper opposite the edge face of the insole.

4. In a lasting machine, wipers movable to wipe the marginal portion of an upper about the toe end of a last inwardly over an insole on the last, a device arranged to engage the insole and to serve as an abutment against which a portion of the lasting margin of the upper around the toe is pressed by the wipers in upstanding relation to the shoe bottom at a distance inwardly from the edge of the insole at the end of the wiping operation, the wipers being shaped to conform substantially to the contour of the portion of the upper pressed against said device, a wiper carrier supporting said wipers and movable to carry them lengthwise of the last toward the end of the toe and also heightwise of the last prior to such action thereof on the upper, other wiping means also supported by said wiper carrier to be moved thereby lengthwise and heightwise of the last and arranged to perform an upwiping operation on the upper in response to the movement of the carrier heightwise of the last, said other wiping means being so mounted as to permit relative movement thereof and the wiper carrier lengthwise of the last, and means supported independently of the wiper carrier for adjustably limiting the movement of said other wiping means by the carrier lengthwise of the last prior to the completion of the movement of the carrier in that direction to position said other wiping means in proper relation to the last for the upwiping operation.

5. In a lasting machine, the combination with wipers for wiping the marginal portion of an upper about the toe end of a last inwardly over an insole on the last, of a wiper carrier supporting said wipers and movable to carry them lengthwise of the last toward the end of the toe and also heightwise of the last prior to such action thereof on the upper, other wiping means also supported by said wiper carrier to be moved thereby lengthwise and heightwise of the last and arranged to perform an upwiping operation on the upper in response to the movement of the carrier heightwise of the last, said other wiping means being so mounted as to permit relative movement thereof and the wiper carrier lengthwise of the last, and means for stopping the movement of said other wiping means lengthwise of the last by the wiper carrier prior to the completion of the movement of the carrier in that direction to position said other wiping means in proper relation to the last for the upwiping operation.

6. In a lasting machine, the combination with wipers for wiping the marginal portion of an upper about the toe end of a last inwardly over an insole on the last, of a wiper carrier supporting said wipers and movable to carry them lengthwise of the last toward the end of the toe

16

and also heightwise of the last prior to such action thereof on the upper, other wiping means also supported by said wiper carrier to be moved thereby lengthwise and heightwise of the last and arranged to perform an upwiping operation on the upper in response to the movement of the carrier heightwise of the last, said other wiping means being so mounted as to permit relative movement thereof and the wiper carrier lengthwise of the last, and means supported independently of the wiper carrier for adjustably limiting the movement of said other wiping means by the carrier lengthwise of the last prior to the completion of the movement of the carrier in that direction to position said other wiping means in proper relation to the last for the upwiping operation.

7. In a lasting machine, the combination with wipers for wiping the marginal portion of an upper about the toe end of a last inwardly over an insole on the last, of a wiper carrier supporting said wipers and movable to carry them lengthwise of the last toward the end of the toe and also heightwise of the last prior to such action thereof on the upper, other wiping means also supported by said wiper carrier to be moved thereby lengthwise and heightwise of the last and arranged to perform an upwiping operation on the upper in response to the movement of the carrier heightwise of the last, said other wiping means being so mounted as to permit relative movement thereof and the wiper carrier lengthwise of the last, a device movably mounted on the wiper carrier for controlling said other wiping means, and a stop into engagement with which said device is carried by the movement of the wiper carrier lengthwise of the last for limiting the movement of said other wiping means in that direction and for thereby positioning said other wiping means in proper relation to the last for the upwiping operation.

8. In a lasting machine, the combination with wipers for wiping the marginal portion of an upper about the toe end of a last inwardly over an insole on the last, of a wiper carrier supporting said wipers and movable to carry them lengthwise of the last toward the end of the toe and also heightwise of the last prior to such action thereof on the upper, other wiping means also supported by said wiper carrier to be moved thereby lengthwise and heightwise of the last and arranged to perform an upwiping operation on the upper in response to the movement of the carrier heightwise of the last, said other wiping means being located at the opposite sides of said wipers from the sides thereof which face the insole when they are over the insole, and means for determining the position of said other wiping means lengthwise of the last at the beginning of the upwiping operation regardless of the limit of the movement of the wiper carrier lengthwise of the last.

9. In a lasting machine, the combination with wipers for wiping the marginal portion of an upper about the toe end of a last inwardly over an insole on the last, of a wiper carrier supporting said wipers and movable to carry them lengthwise of the last toward the end of the toe and also heightwise of the last prior to such action thereof on the upper, other wiping means also supported by said wiper carrier to be moved thereby lengthwise and heightwise of the last and arranged to perform an upwiping operation on the upper in response to the movement of the carrier heightwise of the last, said other wiping means being so mounted as to permit relative movement thereof and the wiper carrier lengthwise of the last, and means supported independently of the wiper carrier for adjustably limiting the movement of said other wiping means by the carrier lengthwise of the last prior to the completion of the movement of the carrier in that direction to position said other wiping means in proper relation to the last for the upwiping operation.

carrier heightwise of the last, said other wiping means being located at the opposite sides of said wipers from the sides thereof which face the insole when they are over the insole, and means for adjustably varying relatively to the wiper carrier the position of said other wiping means lengthwise of the last at the beginning of the upwiping operation.

10. In a lasting machine, the combination with wipers for wiping the marginal portion of an upper about the toe end of a last inwardly over an insole on the last, of a wiper carrier supporting said wipers and movable to carry them lengthwise of the last toward the end of the toe and also heightwise of the last prior to such action thereof on the upper, other wiping means also supported by said wiper carrier to be moved thereby lengthwise and heightwise of the last and arranged to perform an upwiping operation on the upper in response to the movement of the carrier heightwise of the last, and means for adjustably determining the position of said other wiping means lengthwise of the last at the beginning of the unwiping operation regardless of the limit of the movement of the wiper carrier lengthwise of the last, said other wiping means being located at the opposite sides of said wipers from the sides thereof which face the insole when they are over the insole and being yieldingly movable lengthwise of the last relatively to the wiper carrier in response to pressure of the upper thereon in the upwiping operation.

11. In a lasting machine, the combination with wipers for wiping the marginal portion of an upper about the toe end of a last inwardly over an insole on the last, of a wiper carrier supporting said wipers and movable to carry them lengthwise of the last toward the end of the toe and also heightwise of the last prior to such action thereof on the upper, other wiping means also supported by said wiper carrier to be moved thereby lengthwise and heightwise of the last and arranged to perform an upwiping operation on the upper in response to the movement of the carrier heightwise of the last, said other wiping means being located at the opposite sides of said wipers from the sides thereof which face the insole when they are over the insole and being so mounted as to permit relative movement thereof and the wiper carrier lengthwise of the last, and a spring against the resistance of which said other wiping means is movable lengthwise of the last relatively to the wiper carrier in response to pressure of the upper thereon in the upwiping operation.

12. In a lasting machine, the combination with wipers for wiping the marginal portion of an upper about the toe end of a last inwardly over an insole on the last, of a wiper carrier supporting said wipers and movable to carry them lengthwise of the last toward the end of the toe and also heightwise of the last prior to such action thereof on the upper, other wiping means also supported by said wiper carrier, to be moved thereby lengthwise and heightwise of the last and arranged to perform an upwiping operation on the upper in response to the movement of the carrier heightwise of the last, said other wiping means being located at the opposite sides of said wipers from the sides thereof which face the insole when they are over the insole and being so mounted as to permit relative movement thereof and the wiper carrier lengthwise of the last, a device movably mounted on the wiper carrier for controlling said other wiping means, means

arranged to act through said device to limit adjustably the movement of said other wiping means lengthwise of the last when the wiper carrier is moved in that direction, and spring means controlling said device and against the resistance of which said other wiping means is movable lengthwise of the last relatively to the wiper carrier in response to pressure of the upper thereon in the upwiping operation.

- 10 13. In a lasting machine, the combination with wipers for wiping the marginal portion of an upper about the toe end of a last inwardly over an insole on the last, of a wiper carrier supporting said wipers and movable to carry them lengthwise of the last toward the end of the toe and also heightwise of the last prior to such action thereof on the upper, a plate also supported by said wiper carrier to be moved thereby lengthwise and heightwise of the last and having a wiping edge curved to extend about the toe end of the last from one side thereof to the other side for performing an upwiping operation on the upper in response to the movement of the carrier heightwise of the last, said plate being located at the opposite sides of said wipers from the sides thereof which face the insole when they are over the insole and being so mounted as to permit relative movement of the plate and the wiper carrier lengthwise of the last, and means for stopping the movement of said plate lengthwise of the last in the course of the movement of the wiper carrier in that direction to position the plate in proper relation to the last for the upwiping operation.
- 35 14. In a lasting machine, the combination with wipers for wiping the marginal portion of an upper about the toe end of a last inwardly over an insole on the last, of a wiper carrier supporting said wipers and movable to carry them lengthwise of the last toward the end of the toe and also heightwise of the last prior to such action thereof on the upper, a plate also supported by said wiper carrier to be moved thereby lengthwise and heightwise of the last and having a wiping edge curved to extend about the toe end of the last from one side thereof to the other side for performing an upwiping operation on the upper in response to the movement of the carrier heightwise of the last, said plate being located at the opposite sides of said wipers from the sides thereof which face the insole when they are over the insole and being so mounted as to permit relative movement of the plate and the wiper carrier lengthwise of the last, a device movably mounted on the wiper carrier for controlling said plate, and a stop into engagement with which said device is carried by the movement of the wiper carrier lengthwise of the last for limiting the movement of the plate in that direction and for thereby positioning the plate in proper relation to the last for the upwiping operation.
- 65 15. In a lasting machine, the combination with wipers for wiping the marginal portion of an upper about the toe end of a last inwardly over an insole on the last, of a wiper carrier supporting said wipers and movable to carry them lengthwise of the last toward the end of the toe and also heightwise of the last prior to such action thereof on the upper, a plate also supported by said wiper carrier to be moved thereby lengthwise and heightwise of the last and having a wiping edge curved to extend about the toe end of the last from one side thereof to the other side for performing an upwiping operation on the

upper in response to the movement of the carrier heightwise of the last, said plate being located at the opposite sides of said wipers from the sides thereof which face the insole when they are over the insole and being so mounted as to permit relative movement of the plate and the wiper carrier lengthwise of the last, and spring means against the resistance of which said plate is movable lengthwise of the last relatively to the wiper carrier in response to pressure of the upper thereon in the upwiping operation.

16. In a lasting machine, the combination with means for wiping the lasting margin of an upper about the toe end of a last inwardly over an insole on the last, of a device arranged to engage the insole and to serve as an abutment against which a portion of the lasting margin of the upper is pressed by said wiping means in upstanding relation to the shoe bottom at a distance inwardly from the edge of the insole at the end of the wiping operation, means for engaging the bottom face of the insole to position the shoe heightwise independently of said abutment device; said device being mounted to move in directions heightwise of the shoe relatively to said positioning means to permit it to adjust itself to the shoe, and additional means for positioning the shoe lengthwise and widthwise relatively to said abutment device.

17. In a lasting machine, the combination with means for wiping the lasting margin of an upper about the toe end of a last inwardly over an insole on the last, of a device arranged to engage the insole and to serve as an abutment against which a portion of the lasting margin of the upper is pressed by said wiping means in upstanding relation to the shoe bottom at a distance inwardly from the edge of the insole at the end of the wiping operation, means for engaging the bottom face of the insole to position the shoe heightwise independently of said abutment device, said device being mounted to move in directions heightwise of the shoe relatively to said shoe-positioning means, spring means against the resistance of which the device is thus movable initially by the shoe until the shoe engages said positioning means, and additional means for positioning the shoe lengthwise and widthwise relatively to said abutment device.

18. In a lasting machine, the combination with means for wiping the lasting margin of an upper about the toe end of a last inwardly over an insole on the last, of a device arranged to engage the insole and to serve as an abutment against which a portion of the last margin of the upper is pressed by said wiping means in upstanding relation to the shoe bottom at a distance inwardly from the edge of the insole at the end of the wiping operation, means for engaging the bottom face of the forepart of the insole to position the shoe heightwise independently of said abutment device, said device being mounted to move in directions heightwise of the shoe relatively to said shoe-positioning means to permit it to adjust itself to the shoe but being positioned lengthwise and widthwise of the shoe by said positioning means when the upper is pressed against it by the wiping means, and additional means for positioning the shoe lengthwise and widthwise relatively to said abutment device.

19. In a lasting machine, the combination with means for wiping the lasting margin of an upper about the toe end of a last inwardly over an

insole on the last, of a device arranged to engage the insole and to serve as an abutment against which a portion of the lasting margin of the upper is pressed by said wiping means in upstanding relation to the shoe bottom at a distance inwardly from the edge of the insole at the end of the wiping operation, members arranged to engage the bottom face of the forepart of the insole respectively in different locations to position the shoe heightwise independently of said abutment device, said device being mounted to move in directions heightwise of the shoe relatively to said members to permit it to adjust itself to the shoe but being positioned lengthwise and widthwise of the shoe by said members when the upper is pressed against it by the wiping means, and additional members arranged to be positioned opposite the toe-end face and the side faces of the last for positioning the shoe lengthwise and widthwise relatively to said abutment device.

20. In a lasting machine, the combination with means for wiping the lasting margin of an upper about the toe end of a last inwardly over an insole on the last, of a device arranged to engage the insole and to serve as an abutment against which a portion of the lasting margin of the upper is pressed by said wiping means in upstanding relation to the shoe bottom at a distance inwardly from the edge of the insole at the end of the wiping operation, means for engaging the bottom face of the forepart of the insole to position the shoe heightwise independently of said abutment device, said device being removable without disturbing said shoe-positioning means to permit a device of different contour to be substituted, and additional means for positioning the shoe lengthwise and widthwise relatively to said abutment device.

21. In a lasting machine, the combination with means for wiping the lasting margin of an upper about the toe end of a last inwardly over an insole on the last, of a device arranged to engage the insole and to serve as an abutment against which a portion of the lasting margin of the upper is pressed by said wiping means in upstanding relation to the shoe bottom at a distance inwardly from the edge of the insole at the end of the wiping operation, members arranged to engage the bottom face of the forepart of the insole respectively in different locations to position the shoe heightwise independently of said abutment device, said device being positioned lengthwise and widthwise of the shoe by said members and being removable without disturbing said members to permit a device of different contour to be substituted, and additional members arranged to be positioned opposite the toe-end face and the side faces of the last for positioning the shoe lengthwise and widthwise relatively to said abutment device.

22. In a lasting machine, the combination with means for wiping the lasting margin of an upper inwardly over an insole on a last, of a device arranged to engage the insole and to serve as an abutment against which a portion of the lasting margin of the upper is pressed by said wiping means in upstanding relation to the shoe bottom at a distance inwardly from the edge of the insole at the end of the wiping operation, said device being positioned initially nearer the edge of the insole to serve as a hold-down for the marginal portion of the insole and being movable from that position inwardly over the insole in the wiping operation.

23. In a lasting machine, the combination with means for wiping the lasting margin of an upper about the toe end of a last inwardly over an insole on the last, of a device arranged to engage the insole and to serve as an abutment against which a portion of the lasting margin of the upper is pressed by said wiping means in upstanding relation to the shoe bottom at a distance inwardly from the edge of the insole at the end of the wiping operation, said device being positioned initially nearer the edge of the insole at the end of the toe to serve as a holddown for the marginal portion of the insole and being movable from that position inwardly over the insole lengthwise of the shoe by pressure of the marginal portion of the upper against it in the wiping operation.

24. In a lasting machine, the combination with means for wiping the lasting margin of an upper about the toe end of a last inwardly over an insole on the last, of a device arranged to engage the insole and to serve as an abutment against which a portion of the lasting margin of the upper is pressed by said wiping means in upstanding relation to the shoe bottom at a distance inwardly from the edge of the insole at the end of the wiping operation, said device being positioned initially nearer the edge of the insole at the end of the toe to serve as a holddown for the marginal portion of the insole and being movable from that position inwardly over the insole lengthwise of the shoe in the wiping operation, a spring against the resistance of which the device is thus movable, and means for positively stopping such movement of the device while a portion of the lasting margin of the upper is still between it and the wiping means.

25. In a lasting machine, the combination with means for wiping the lasting margin of an upper about the toe end of a last inwardly over an insole on the last, of a device arranged to engage the insole and to serve as an abutment against which a portion of the lasting margin of the upper is pressed by said wiping means in upstanding relation to the shoe bottom at a distance inwardly from the edge of the insole at the end of the wiping operation, said device being positioned initially nearer the edge of the insole at the end of the toe to serve as a holddown for the marginal portion of the insole, a latch for holding the device detachably in place in the machine, and a spring against the resistance of which the device is movable with said latch from its initial position inwardly over the insole lengthwise of the shoe by pressure of the marginal portion of the upper against it in the wiping operation.

26. In a lasting machine, the combination with means for wiping the lasting margin of an upper about the toe end of a last inwardly over an insole on the last, of a device arranged to engage the insole and to serve as an abutment against which a portion of the lasting margin of the upper is pressed by said wiping means in upstanding relation to the shoe bottom at a distance inwardly from the edge of the insole at the end of the wiping operation, said device being positioned initially nearer the edge of the insole at the end of the toe to serve as a holddown for the marginal portion of the insole and being movable from that position inwardly over the insole lengthwise of the shoe in the wiping operation, and means relatively to which the device is thus inwardly movable for engaging the bottom face of the forepart of the insole to position the shoe heightwise independently of said device.

27. In a lasting machine, the combination with

means for wiping the lasting margin of an upper about the toe end of a last inwardly over an insole on the last, of a device arranged to engage the insole and to serve as an abutment against which a portion of the lasting margin of the upper is pressed by said wiping means in upstanding relation to the shoe bottom at a distance inwardly from the edge of the insole at the end of the wiping operation, said device being positioned initially nearer the edge of the insole at the end of the toe to serve as a holddown for the marginal portion of the insole and being movable from that position inwardly over the insole lengthwise of the shoe in the wiping operation, and means for engaging the bottom face of the forepart of the insole to position the shoe heightwise independently of said abutment device, said positioning means being arranged to guide the device in its inward movement over the insole.

28. In a lasting machine, the combination with means for wiping the lasting margin of an upper about the toe end of a last inwardly over an insole on the last, of a device arranged to engage the insole and to serve as an abutment against which a portion of the lasting margin of the upper is pressed by said wiping means in upstanding relation to the shoe bottom at a distance inwardly from the edge of the insole at the end of the wiping operation, said device being positioned initially nearer the edge of the insole at the end of the toe to serve as a holddown for the marginal portion of the insole and being movable from that position inwardly over the insole lengthwise of the shoe in the wiping operation, and means relatively to which the device is thus inwardly movable for engaging the bottom face of the forepart of the insole to position the shoe heightwise independently of said device, said positioning means being arranged to provide a stop for said device to limit its inward movement over the insole.

29. In a lasting machine, the combination with toe-lasting means, of means for positioning the toe end of a shoe and its last lengthwise and widthwise relatively to said toe-lasting means when the shoe is presented to the machine, and additional means arranged to engage the opposite side faces of the forepart of the shoe in locations farther heelward than its toe-end portion further to position the shoe and last when the shoe is thus presented.

30. In a lasting machine, the combination with toe-lasting means, of means for positioning the toe end of a shoe and its last lengthwise and widthwise relatively to said toe-lasting means when the shoe is presented to the machine, and members arranged to engage the opposite side faces of the forepart of the shoe in locations farther heelward than its toe-end portion further to position the shoe and last, said members being connected together for equal movements toward or from each other and being thus movable away from each other by wedging action of the shoe thereon when the shoe is thus presented.

31. In a lasting machine, the combination with toe-lasting means, of means for positioning a shoe and its last relatively to said toe-lasting means when the shoe is presented to the machine, said positioning means including a member arranged to engage the toe-end face of the last and other members arranged to engage the opposite side faces of the forepart of the shoe in locations farther heelward than its toe-end portion, the first-named member being displace-

able to permit the operation of the toe-lasting means.

32. In a lasting machine, the combination with toe-lasting means, of means for positioning a shoe and its last relatively to said toe-lasting means, said positioning means including a member arranged to serve as an abutment opposite the toe-end face of the last and other members arranged to engage the opposite side faces of the forepart of the shoe in locations farther heelward than its toe-end portion, said other members being connected together for equal movements away from each other by wedging action of the shoe thereon in response to heightwise movement of the portion of the shoe which they engage when the shoe is presented to the machine.

33. In a lasting machine, the combination with toe-lasting means, of means for positioning a shoe and its last relatively to said toe-lasting means, said positioning means comprising a plurality of gages arranged respectively to serve as abutments opposite the end and side faces of the toe-end portion of the last and other gages arranged to engage the opposite side faces of the forepart of the shoe in locations farther heelward than its toe-end portion.

34. In a lasting machine, the combination with toe-lasting means, of means for positioning a shoe and its last relatively to said toe-lasting means, said positioning means including gages arranged to be positioned respectively opposite the end and side faces of the toe-end portion of the last, the side gages being mounted for movements toward or from each other about axes extending heightwise of the last, and other gages arranged to engage the opposite side faces of the forepart of the shoe in locations farther heelward than its toe-end portion, said other gages being mounted for movements toward or from each other about axes extending lengthwise of the shoe.

35. In a lasting machine, the combination with toe-lasting means, of means for positioning a shoe and its last relatively to said toe-lasting means, said positioning means including gages arranged to be positioned respectively opposite the end and side faces of the toe-end portion of the last, means connecting the side gages together for equal movements away from each other by wedging action of the shoe thereon when the shoe is presented to the machine, other gages arranged to engage the opposite side faces of the forepart of the shoe in locations farther heelward than its toe-end portion, and means connecting said other gages together for equal movements away from each other by wedging action of the shoe thereon when the shoe is thus presented.

36. In a lasting machine, the combination with toe-lasting means, of means for positioning a shoe and its last relatively to said toe-lasting means, said positioning means including gages arranged to be positioned respectively opposite the end and side faces of the toe-end portion of the last, the side gages being mounted for movements away from each other by wedging action of the shoe thereon in response to lengthwise movement of the shoe when it is presented to the machine, and other gages arranged to engage the opposite side faces of the forepart of the shoe in locations farther heelward than its toe-end portion, said other gages being mounted for movements away from each other by wedging action of the shoe thereon in response to height-

wise movement of the portion of the shoe which they engage when the shoe is thus presented.

37. In a lasting machine, the combination with toe-lasting means, of means for positioning a shoe and its last relatively to said toe-lasting means when the shoe is presented to the machine, said positioning means including a member arranged to serve as an abutment opposite the toe-end face of the last and other members arranged to engage the opposite side faces of the forepart of the shoe in locations farther heelward than its toe-end portion, said first-named member being movable out of its operative position in the course of the operation of the machine while the shoe is still engaged by said other members.

38. In a lasting machine, the combination with toe-lasting means, of means for positioning a shoe and its last relatively to said toe-lasting means when the shoe is presented to the machine, said positioning means including a member arranged to serve as an abutment opposite the toe-end face of the last and other members arranged to engage the opposite side faces of the forepart of the shoe in locations farther heelward than its toe-end portion, said first-named member being movable out of its operative position in the course of the operation of the machine while the shoe is still engaged by said other members.

39. In a lasting machine, the combination with toe-lasting means, of means for positioning a shoe and its last relatively to said toe-lasting means, said positioning means comprising a plurality of gages arranged respectively to serve as abutments opposite the end and side faces of the toe-end portion of the last and other gages arranged to engage the opposite side faces of the forepart of the shoe in locations farther heelward than its toe-end portion, and mechanism for moving said first-named member heightwise of the shoe out of operative position in the course of the operation of the machine while the shoe is still engaged by said other members.

40. In a lasting machine, the combination with toe-lasting means, of means for positioning a shoe and its last relatively to said toe-lasting means when the shoe is presented to the machine, said positioning means comprising a plurality of gages arranged respectively to serve as abutments opposite the end and side faces of the toe-end portion of the last and other gages arranged to engage the opposite side faces of the forepart of the shoe in locations farther heelward than its toe-end portion, and means for withdrawing said first-named gages from their operative positions in the course of the operation of the machine while the shoe is still engaged by said other gages.

41. In a lasting machine, the combination with toe-lasting means, of a plurality of gages arranged to serve as abutments opposite the end and side faces of the toe-end portion of a last for positioning the last and its shoe materials lengthwise and widthwise relatively to said toe-lasting means when the shoe is presented to the machine, said gages being guided independently of one another for movements heightwise of the shoe to withdraw them from operative positions in the course of the operation of the machine, and means connecting said gages together for movements in unison when they are thus withdrawn.

42. In a lasting machine, the combination with toe-lasting means, of a plurality of gages comprising an end gage and opposite side gages arranged to serve as abutments opposite the end and side faces of the toe-end portion of a last

for positioning the last and its shoe materials lengthwise and widthwise relatively to said toe-lasting means when the shoe is presented to the machine, said gages being guided independently of one another for sliding movements heightwise of the shoe out of operative positions, and automatic means for thus moving said gages in the course of the operation of the machine.

for positioning the toe end of the last and its shoe materials lengthwise and widthwise relatively to said toe-lasting means when the shoe is presented to the machine, and members movable widthwise of the last with the side gages to adjust them toward or from each other, the side gages being movable with the end gage heightwise of the last relatively to said members away from their operative positions in the course of the operation of the machine.

43. In a lasting machine, the combination with toe-lasting means, of a plurality of gages comprising an end gage and opposite side gages arranged to serve as abutments opposite the end and side faces of the toe-end portion of a last for positioning the toe end of the last and its shoe materials lengthwise and widthwise relatively to said toe-lasting means when the shoe is presented to the machine, and members connected together for equal movements widthwise of the last with the side gages to adjust them toward or from each other, the side gages being slidably mounted in said members for movements heightwise of the last with the end gage away from their operative positions in the course of the operation of the machine.

44. In a lasting machine, the combination with toe-lasting means, of a plurality of gages comprising an end gage and opposite side gages arranged to serve as abutments opposite the end and side faces of the toe-end portion of a last for positioning the toe end of the last and its shoe materials lengthwise and widthwise relatively to said toe-lasting means when the shoe is presented to the machine, members mounted for movements widthwise of the last with the side gages to adjust them toward or from each other, mechanism connected to the end gage for automatically moving it heightwise of the last to withdraw it from operative position in the course of the operation of the machine, and means connecting said mechanism to the side gages for moving them heightwise of the last relatively to said adjusting members to withdraw them also with the end gage regardless of their adjusted positions.

45. In a lasting machine, the combination with means for wiping the toe end of an upper on a last into lasted position, and a carrier supporting said wiping means and movable heightwise of the last to cause said means to wipe the upper in that direction, of a gage arranged to serve as a toe-end abutment for positioning the last and shoe lengthwise when the shoe is presented to the machine, means providing a guideway located substantially opposite the bottom of the last and along which said gage is movable heightwise of the last, and mechanism arranged to be operated by the movement of said carrier heightwise of the last for moving the gage along said guideway to withdraw it from operative position.

46. In a lasting machine, the combination with means for wiping the toe end of an upper on a last into lasted position, and a carrier supporting said wiping means and movable heightwise of the last to cause said means to wipe the upper in that direction, of a gage arranged to serve as a toe-end abutment for positioning the last and shoe lengthwise when the shoe is presented to the machine, means providing a guideway along which said gage is movable heightwise of the last, and mechanism including a link pivotally connected to said carrier and arranged to be operated by the movement of the carrier heightwise of

the last for moving the gage along said guideway to withdraw it from operative position.

47. In a lasting machine, the combination with means for wiping the toe end of an upper on a last into lasted position, and a carrier supporting said wiping means and movable heightwise of the last to cause said means to wipe the upper in that direction, of a gage arranged to serve as a toe-end abutment for positioning the last and shoe lengthwise when the shoe is presented to the machine, an arm mounted for swinging movement heightwise of the last and connected to said gage, and mechanism including a link connected to said carrier for operating said arm to withdraw the gage from operative position by the movement of the carrier heightwise of the last.

48. In a lasting machine, the combination with means for wiping the toe end of an upper on a last into lasted position, and a carrier supporting said wiping means and movable heightwise of the last to cause said means to wipe the upper in that direction, of a gage arranged to serve as a toe-end abutment for positioning the last and shoe lengthwise when the shoe is presented to the machine, means providing a guideway along which said gage is movable heightwise of the last, mechanism connected to the gage for moving it along said guideway, and a link arranged to extend heightwise of the last and movable lengthwise by said carrier to operate said mechanism and thereby to withdraw the gage from operative position.

49. In a lasting machine, the combination with means for wiping the toe end of an upper on a last into lasted position, and a carrier supporting said wiping means and movable heightwise of the last to cause said means to wipe the upper in that direction, of a gage arranged to serve as a toe-end abutment for positioning the last and shoe lengthwise when the shoe is presented to the machine, an arm mounted for swinging movement heightwise of the last, a link connecting the gage to said arm, another arm mounted for swinging movement with said first-named arm, and a link extending heightwise of the last from said other arm and arranged to be operated by said carrier to withdraw the gage from operative position by the movement of the carrier heightwise of the last.

50. In a lasting machine, the combination with means for wiping the toe end of an upper on a last into lasted position, and a carrier supporting said wiping means and movable heightwise of the last to cause said means to wipe the upper in that direction, of a plurality of gages comprising an end gage and opposite side gages arranged to serve as abutments for positioning the toe end of the last and its shoe materials lengthwise and widthwise when the shoe is presented to the machine, said gages being guided independently of one another for movements heightwise of the last, and means for thus moving the gages to withdraw them from operative positions by the movement of said carrier heightwise of the last.

51. In a lasting machine, the combination with means for wiping the toe end of an upper on a last into lasted position, and a carrier supporting said wiping means and movable heightwise of the last to cause said means to wipe the upper in that direction, of a plurality of gages comprising an end gage and opposite side gages arranged to serve as abutments for positioning the toe end of the last and its shoe materials lengthwise and widthwise when the shoe is presented to the machine, the side gages being adjustable toward and

27

from each other widthwise of the last, and means connected to all said gages for moving them heightwise of the last to withdraw them from their operative positions by the movement of said carrier heightwise of the last.

52. In a lasting machine, the combination with means for wiping the toe end of an upper on a last into lasted position, and a carrier supporting said wiping means and movable heightwise of the last to cause said means to wipe the upper in that direction, of a plurality of gages comprising an end gage and opposite side gages arranged to serve as abutments for positioning the toe end of the last and its shoe materials lengthwise and widthwise when the shoe is presented to the machine, said gages being guided independently of

10

Certificate of Correction

Patent No. 2,446,330.

August 3, 1948.

ERIC A. HOLMGREN

It is hereby certified that errors appear in the printed specification of the above numbered patent requiring correction as follows: Column 15, line 13, claim 3, for "wips" read *wipe*; column 17, line 24, claim 10, for "unwiping" read *upwiping*; column 19, line 56, claim 18, for "last" read *lasting*; and that the said Letters Patent should be read with these corrections therein that the same may conform to the record of the case in the Patent Office.

Signed and sealed this 23rd day of November, A. D. 1948.
